POST-MOUNTED PLAYGROUND CLIMBER

Eva R. Reichl, 244 Connecting Road,
Mount Lebanon Township, Pa. 15228

Filed June 5, 1969, Ser. No. 17,523

Term of patent 14 years

Int. Cl. D21—03

U.S. Cl. D34—5

The figure is a perspective view of a playground climber showing my design.

I claim:

The ornamental design for a post-mounted playground climber, as shown.
